METHOD OF AND APPARATUS FOR CONJUGATE GRINDING OF IRREGULARLY SHAPED ARTICLES

Carl E. Clutter, Mason, Thomas E. Dugle, Cincinnati, Michael Field, Indian Hill, and Frank M. Foster, Cincinnati, Ohio, assignors, by mesne assignments, to Metcut Research Associates, Cincinnati, Ohio, a partnership

Application April 20, 1953, Serial No. 349,778

16 Claims. (Cl. 51—143)

This invention relates to a method of and apparatus for grinding irregularly shaped articles, such as, by way of example, the blades and buckets of gas turbines, by passing an endless abrasive belt between the said irregularly shaped article and a conjugate form.

An object of the invention is to teach a method of grinding both the concave and convex surfaces of an irregularly shaped article by means of an endless abrasive belt passed between the article and a conjugate form while the article or the form is being moved along a guided path for sequentially disposing the surface of the form in conjugate coincidence with portions of the surface of the article.

Another object of the invention is to provide simple yet highly effective devices for enabling our method of grinding to be mechanically performed, in lieu of by hand.

A further object of the invention is to provide a device for accurately grinding concave surfaces in an article by means of a conjugate form mounted for planetary cyclic motion relative thereto for guiding an abrasive belt over the surface of the article.

Another object of the invention is to provide a device for accurately grinding convex surfaces in an article by means of a fixedly mounted conjugate form relative to which the article is moved in a planetary cyclic motion.

Still another object of the invention is to provide grinding devices having the hereinabove described characteristics, with means for accurately controlling the rate at which the grinding is effected.

Another object of the invention is to provide simple and effective means for automatically equalizing the tension across the face of an endless abrasive belt after leaving the conjugate form.

These and other objects are attained by the means described herein and as disclosed in the accompanying drawings, in which:

Fig. 1 is a front elevation of a device embodying the teachings of the present invention, which is particularly adapted for grinding concave surfaces on an article.

Fig. 2 is a view, partly in section, taken along line 2—2 of Fig. 1.

Fig. 3 is a sectional view of the conjugate form supporting means and its actuating mechanism only taken on line 3—3 of Fig. 1.

Fig. 4 is a partial elevational view of the right end of Fig. 3.

Fig. 5 is a top view of Fig. 4.

Fig. 6 is a view of the left end of the conjugate form and spindle only of Fig. 3.

Fig. 7 is a sectional view taken on line 7—7 of Fig. 6.

Fig. 8 is a sectional view taken on line 8—8 of Fig. 1.

Fig. 9 is a sectional view taken on line 9—9 of Fig. 8.

Fig. 10 is a sectional view taken on line 10—10 of Fig. 3.

Fig. 11 is a front elevation of a device embodying the teachings of the present invention, which is particularly adapted for grinding convex surfaces on an article.

2

Fig. 12 is a view, partly in section, taken along line 12—12 of Fig. 11.

Fig. 13 is a sectional view taken on line 13—13 of Fig. 11.

Fig. 14 is an elevational view of the left end of Fig. 13 with parts thereof being broken away for clarity of detail and understanding.

Fig. 15 is a top view of Fig. 14 with the top cover thereof removed, and with the control housing in cross section for clarity of detail and understanding.

Fig. 16 is a sectional view on line 16—16 of Fig. 15.

Fig. 17 is a sectional view of the article supporting cradle and its actuating mechanism only taken on line 17—17 of Fig. 11.

Fig. 18 is an elevational view of the right end of Fig. 17.

Fig. 19 is a sectional view taken on line 19—19 of Fig. 17.

Figs. 20 and 21 are schematic views illustrating the sequential steps followed in grinding the convex surface of the airfoil shape of the blade or bucket for a turbine type engine, Fig. 20 illustrating a compressor blade, Fig. 21 illustrating a turbine bucket.

Fig. 22 is a diagrammatic view of the fluid control system comprising a detail of the present invention.

At the outset it should be noted that the present invention embodies simple, yet highly effective means for quickly and accurately grinding to any desired finish concave or convex surfaces on irregularly shaped articles by guiding an endless abrasive belt over a conjugate form, and of moving either the article or conjugate form, but not both, for disposing the surface of the form in conjugate coincidence with the surface of the article throughout the grinding operation. We are well aware that the surfaces of irregular articles such as turbine blades and buckets have heretofore been ground to size, by means of an endless abrasive belt which is caused to pass between a conjugate form and that surface of the article to be ground, wherein both the article and the conjugate form are simultaneously moved in timed relationship.

In sharp contrast thereto we effect conjugate grinding of the surface of irregularly shaped articles by passing an endless belt between the article to be ground and a conjugate form wherein the article is held immovable and stationary in two planes for movement in a third plane toward and away from the conjugate form and wherein the conjugate form is caused to move in a predetermined path relative to the article so that the surface of the form is coincident with the surface of the article at all points of contact throughout the movement of the form about or relative to the article, in those instances when a concave surface is being ground. Conversely, when convex surfaces are to be ground, the conjugate form is held immovable and stationary in two planes for movement in a third plane relative to the article which is mounted for movement along a predetermined path relative to the form whereby the surface of the form will be coincident with the surface of the article as it is moved about or relative to the form.

For clarity of detail and understanding, we shall first describe one type of means which has given uniformly excellent results in grinding the convex surface of irregularly shaped articles.

With particular reference now to Fig. 11, the numeral 30 denotes, generally, a housing which includes a rear wall 32 to which an oscillatable blade cradle is mounted.

With particular reference now to Fig. 17, the numeral 34 denotes an inner cradle and the numeral 36 an outer cradle. The upper end of forward wall 38 of the outer cradle is pivotally journaled to front wall or bearing column 40 as at 42. The upper end of the rear wall 44 of the outer cradle is secured to and carried by spindle

46, by means of bolts or other suitable retaining means 48.

Spindle 46 is journaled within housing 50 by means of suitable anti-friction elements 52 and 54. A gear 56 is keyed to portion 47 of the spindle, said gear engaging rack 58, the reciprocation of said rack being utilized to rotate the spindle in opposite directions for imparting an oscillatory motion to outer cradle 36.

The upper end of the forward wall 60 of the inner cradle is suitably journaled as at 62 to the forward wall 38 of the outer cradle at a location below the pivotal mounting of the front wall of the outer cradle to bearing column 40. The rear wall 64 of the inner cradle is keyed to the forward end of shaft 66, said shaft being journaled in bearings 68 and 70 to the rear wall 44 of the outer cradle.

A planet gear 72 is keyed to that end of shaft 66 remote from the inner cradle, said gear being in normal driven relationship with sun gear 74 secured to and carried by the forward end of a stationary shaft 76. Shaft 76 is rigidly and non-rotatably mounted with respect to housing 50 by means of clamp plate 78 which, as best illustrated in Fig. 18, may be secured to housing 50 by means of bolts 80. In the preferred embodiment of the invention clamp plate 78 is provided with means, such as a slit 82 and a slot 84 in radial alignment with the clamp plate in order that said plate may be securely though releasably fastened to the free outer end of shaft 76 by means of a bolt 86 which when tightened will draw the opposite portions of slot 84 together for clamping the shaft.

Still referring to Fig. 18, it will be noted that rack 58, hereinafter referred to as the power rack, is adapted to be reciprocated by means of a pair of opposed pistons 90 and 92 of cylinders 94 and 96, respectively, which are suitably secured in axial alignment to opposite ends of a block 98 such as, by way of example, tie rods 95, note Figs. 4 and 5, which extend through and interconnect end plates 97 and 99, respectively. The rack is mounted to reciprocate within the block which, note Fig. 17, is suitably fastened to wall 100 of housing 50.

Fluid media under pressure is alternately introduced into cylinders 94 and 96 for driving the rack 58 toward one end or the other of its stroke, it being noted that the opposite ends of the rack, note Fig. 18, are provided with reduced contact areas 102 against which the outer faces of pistons 90 and 92 abuttingly engage.

With reference now to Figs. 17 and 18, it will be noted that spur gear 104 is rigidly secured to portion 47 of spindle 46, said gear engaging the teeth of control rack 106. A pair of dogs 108 and 110 are secured to and carried by control rack 106 for selectively engaging levers 112 and 114, respectively, of reversing valve denoted generally by the numeral 116, it being understood that this valve controls the flow of fluid under pressure, from a suitable source, not illustrated, alternately to either of cylinders 94 or 96. If desired, valve 116 may be a pilot valve for actuating a main, master, or control valve for the actuating fluid delivered to cylinders 94 and 96. In Fig. 22 the valve 116 is shown as a pilot valve for actuating the master reversing valve 120 which controls the flow of fluid from pressure line 200 to either one or the other of cylinders 96 and 94 for thereby shifting the power rack from one end of its stroke to the other. The structural details and operating cycle of valves 116 and 120 will hereinafter be more fully discussed.

With reference now to Fig. 18, it will be noted that control rack 106 will be translated to the left by rotation of gear 104 until such time as dog 108 contacts lever 112 which will be shifted for changing the flow of fluid from cylinder 94 to cylinder 96, thereby reversing the direction or travel of power rack 58 to the right, and thereby reversing the direction of rotation of spindle 46, gear 104 and rack 106.

It will be noted that rotation of spindle 47 will cause the outer cradle 36 to oscillate or rock about an axis extending through stationary shaft 76 and pivot 42. This oscillation will cause the planet gear 72 of the inner cradle 34 to be driven by sun gear 74 which is secured to and carried by stationary shaft 76, for thereby imparting a planetary motion to the inner cradle. It will be noted that the motion thus imparted to inner cradle 34 will be relative to the outer cradle 36, said motion being likewise relative to the framework of the machine.

Suitable means, such as a mounting pad 122, are provided on the inner cradle for securely though releasably clamping an article, such as, by way of example, a blade having an irregular convex surface which is to be ground. The present invention is neither directed to nor concerned with the particular means utilized for thus securely though releasably fastening a blade relative to the pad of the inner cradle.

With particular reference now to Fig. 11, the numeral 130 denotes an endless abrasive belt which passes over idler pulleys 132, 134, a tensioning pulley 136, drive pulley 138 and over the outer face 140 of a conjugate form 141 fixedly mounted relative to and carried by feed arm 142. Drive pulley 138 may be keyed to shaft 144 of an electric motor denoted generally by the numeral 146, said motor being utilized to drive the endless belt at a substantially constant lineal speed.

As best illustrated in Figs. 11 and 12, feed arm 142 is securely fastened to shaft 148, said shaft being rotatably journaled in bearings 150 and 152 in walls 154 and 156, respectively, of housing 30. Shaft 148 is rotated by means of lever 158, the upper end of which is suitably clamped onto a free end of the shaft, see Fig. 12. The opposite end of the lever is pivoted at 160 to a clevis 162 secured to and carried by piston rod 164 of a cylinder 166 pivotally mounted as at 168 to a mounting bracket 170.

The weight of feed arm 142 is simply and effectively counter-balanced by means of spring 172 which surrounds rod 174 pivotally secured to the lower end of lever 158 at 176, and which freely passes through vertical leg 178 of a bracket 180 carried by wall 1180. The free outer end of the rod is provided with a stop element 182, spring 172 being disposed between adjacent faces of leg 178 and element 182, whereby axial movement of rod 174 to the left will be resiliently resisted by the counterforce of spring 172.

It will be understood that the application of fluid pressure to cylinder 166 will move lever 158 and arm 142 in a clockwise direction about shaft 148 for thereby lowering that end of the feed arm remote therefrom.

In the preferred embodiment of the invention the downward motion of the feed arm 142 is controlled by the operating characteristics of a post 210, the upper free end of which is adapted to be contacted by the free lower end of a rest button 212 fixedly secured to and depending from feed arm 142. The travel of post 210 is accomplished in two stages, a rapid and a slow feed, said rates of feed being controlled by means of the post actuating mechanism illustrated in Figs. 13-16, inclusive. Post 210 is mounted for free axial movement within bushing 214 mounted in vertical leg of a housing 216. The lower end of post 210 terminates in an inclined surface 218, and if desired this inclined surface may be incorporated in a shoe suitably secured to and carried by the post. Axial movement of post 210 is controlled and determined by the relative position of wedge 220 movable axially in a direction at right angles with the longitudinal axis of post 210. Axial movement of wedge 220 is accomplished by means of yoke 224 which is shiftable axially of and in a horizontal direction along and between laterally spaced walls 226 and 228 of a top cover denoted generally by the numeral 230, see Fig. 14. An axially disposed elongated groove 232 having opposed parallel side walls 234 and 236 and a bottom wall 238

is provided in lower case 240 and between front and rear walls 242 and 244.

As best illustrated in Fig. 13, a feed wedge 220, a sizing wedge 246 and an intermediate wedge 248 are mounted within elongated groove 232, wherein the feed and sizing wedges are mounted for endwise movement in a horizontal plane, the intermediate wedge 248 being mounted for transverse movement in a vertical plane.

A fluid actuated cylinder 250 is provided with its piston in driven relationship with yoke 224 via piston rod 252 suitably secured to the end wall of the yoke whereby movement of the piston rod will be imparted to the yoke.

With reference now to Figs. 11 and 13, it should be noted that arm 142 will be elevated after each grinding cycle and before the initiation of a subsequent grinding cycle and that when said arm is in its elevated non-operative position, rest button 212 will be spaced above and out of contact with the upper end of post 210. Post 210 will likewise be elevated to the fully advanced position illustrated in broken outline in Fig. 13, it being understood that the feed wedge 220 will be disposed in a fully advanced position to the left for thereby shifting post 210 to a fully elevated position.

With reference to Fig. 15, the numeral 254 denotes a control rod one end of which is secured to and carried by yoke 224; the other end of the rod is provided with a camming surface 256 and a free outer end 258. A suitable limit switch denoted generally by the numeral 260 having a contact arm 262 is mounted adjacent the axial travel of rod 254 whereby contact element 262 of the switch will be actuated incident to movement of rod 254 to the right.

When contact arm 262 is elevated or engaged by camming face 256 of rod 254, switch 260 is utilized to interrupt an electrical circuit to solenoid 480 of a fluid valve 476, see Fig. 22, for decreasing the rate of flow of actuating fluid from cylinder 250, thereby slowing the linear movement of feed wedge 220 to the right, resulting in lowering of post 210 at a lesser rate.

The lowering cycle of the feed arm 142 is as follows: Initially it will be rapidly lowered from a fully raised or elevated position until stop button 212 engages the free upper end of fully elevated post 210. As will herein-after be more fully explained, fluid pressure is applied to cylinder 250 after contact button 212 of the feed ram 142 has engaged the upper end of the fully elevated post 210 for shifting wedge 220 to the right for rather rapidly lowering post 210. Then, after switch 260 has been actuated by rod 254, the rate of actuation of the feed wedge will be materially lessened, incident to operation of valve 476, for materially decreasing the rate at which the post and feed arm 142 is lowered. It should be understood that fluid pressure will be continuously applied to cylinder 166 during the entire grinding cycle for exerting a constant lowering force to the feed arm, said force being opposed by post 210.

With reference again to Fig. 13, it will be noted that the lower surface 270 of feed wedge 220 rests upon and slidably engages the upper horizontal surface 272 of the intermediate wedge 248. The lower surface 274 of the sizing wedge 246 rests upon and slidably engages lower wall 238 of the elongate groove 232, and inclined surface 276 of the intermediate wedge 248 rests on and slidably engages inclined surface 278 of the sizing wedge.

Suitable means are provided for imparting axial movement to the sizing wedge for shifting its lower surface over bottom wall 238 of the groove 232. Movement of the sizing wedge to the right will lift intermediate wedge 248 upwardly, thereby elevating its upper surface 272 on which the feed wedge 220 rides. In this manner height of the reference surface 272 is determined. It will be noted that the opposite ends 280 and 282 are disposed between and slidably engage the respective inner faces of forward and rear walls 242 and 244.

Axial movement of the sizing wedge 246 may be effect-

ed by means of a lead screw 284 which threadably engages nut 286 securely though releasably fastened to the wedge by means of retaining plate 288 fastened to the end of the wedge by means of bolts 290. The lead screw is rotatably journaled in plate 292 by bearings 294, said lead screw being thus retained against endwise axial movement. Preferably the free outer end of the lead screw is provided with a socket 296 for the reception of a suitable key, or the like, by which rotary motion may be imparted to the screw.

In the preferred embodiment of the invention suitable means such as, by way of example, a commercially available counter denoted generally by the numeral 298, is connected by gears 300, 302 and 304 to gear 306 formed integral with lead screw 284, whereby rotation of lead screw 284 will actuate the counter mechanism, thereby enabling an operator to locate the relative position of the sizing wedge by noting the indicia appearing on the counter, it being further noted that the relative horizontal position of the sizing wedge determines the vertical position of post 210.

With reference now to Figs. 14, 15 and 16, the numeral 310 denotes a second lead screw which threadably engages an internally threaded non-symmetrical sleeve 312, the inner end of which terminates in an abutment 314, said sleeve and abutment being mounted for endwise movement in a complementary channelway 316. A stop 318 secured to and carried by yoke 224 is adapted to engage abutment 314 for determining and limiting the maximum forward endwise travel of the yoke and its associated feed wedge 220 incident to shifting of the yoke to the left, to its fully advanced position under the influence of a moving force applied through cylinder 250. In other words, the relative position of abutment 314 determines the maximum height of post 210 for any given setting of the sizing wedge 246.

As in the case of lead screw 284, suitable means are provided in association with lead screw 310 for enabling an operator to ascertain and/or pre-set abutment 314 for effecting a desired maximum elevation of post 210.

As illustrated in Fig. 15, a third lead screw 320 threadably engages a non-symmetrical sleeve 322 mounted for endwise movement in a non-symmetrical channelway 324. A rod 326 is secured to and carried by sleeve 322, the end of said rod projecting through a suitable opening in end wall 244. Switch 260 is secured to and carried by rod 326, it being noted that the relative location of switch 260 and its arm 262 may be shifted to the right or to the left for thereby determining the end of the initial or rapid feed of the feed wedge 220.

Suitable indicating means such as a counter-mechanism 298 is associated with lead screw 320, as with lead screw 310 and 284, for enabling an operator to accurately pre-set the relative position of switch 260 for controlling initiation of the slow feed cycle of the feed wedge.

From the foregoing, it will be noted that an operator may, by merely observing the indicia appearing at windows on the various counter-mechanism 298 associated with each of the various lead screws 284, 310 and 320, accurately determine the limits and relative cycle phases of and through which the post 210 is moved incident to actuation of feed arm 142.

A conjugate form 141 having a cam surface 140, which is coincident with the finished surface to be imparted to the article mounted on the inner cradle 34 is secured to and fixedly mounted relative to feed arm 142 by means of a suitable bracket 330 fastened to said arm by means of bolts 332. It will be noted that the outer surface of conjugate form 141 is so related to the surface of the article as to provide substantial line contact with the article as it is moved by the inner cradle 34 relative to the form 141.

For a more complete understanding of the relationship which occurs between the conjugate cam surface and

the blade, reference is made to Figs. 20 and 21, wherein the numeral 74 denotes the sun gear and the numeral 72 the planet gear of Fig. 17. It will be noted that belt 130 contacts outer surface 140 of the conjugate form 141 between points A and B, the direction of belt travel over the conjugate form being indicated by the headed arrow 334, it being understood that the abrasive surface of the belt is positioned away from the outer surface of the conjugate form.

The letters C, C1, C2, C3, C4 and C5 illustrate the manner in which an article, in this case a blade, secured to and carried by inner cradle 34 is presented to the outer surface of the conjugate form incident to the relative motion and oscillation of the inner and outer cradles relative to the fixed form, it being understood that these relationships are constant throughout the grinding cycle of a particular blade. It should likewise be understood that the path through which the conjugate form 141 is moved incident to lowering of the feed arm 142 is along a substantially vertical axis during the grinding operation and that deviation from straight linear movement of the conjugate form is so minute as to be disregarded for all practical purposes.

With reference now to Fig. 17, it will be noted that the interior of stationary shaft 76 is hollow as at 340 for providing a passageway through which a quantity of coolant may be introduced via nipple 342 threadably engaging the free outer end of shaft 76. A fluid conduit 344 is provided in the rear wall 44 of outer cradle 36, said conduit being in open communication, as at 346, with the interior of shaft 76. A pair of laterally spaced distribution channels 348 (note Fig. 19) are provided along and interiorly of outer cradle 36, said distribution channels being in open communication with a plurality of discharge openings 350, whereby coolant introduced via hollow shaft 76 will be discharged upwardly for thoroughly drenching the blade and both sides of the endless belt during the grinding process.

Automatic controls

In Fig. 22 we have diagrammatically illustrated the various fluid controls which are utilized for enabling an operator to manually initiate a grinding cycle after having mounted an article on the pad 122 of the inner cradle whereby the convex surface of the article will be automatically ground and the machine automatically stopped at the completion of the grinding cycle for enabling the operator to remove the finished article and insert another article preparatory to the next grinding cycle.

In Fig. 22 the numeral 400 denotes generally a pump for circulating a fluid from a sump or reservoir 402 through a pressure line 200, the numeral 404 denoting a drain line under atmospheric pressure and the numeral 406 an exhaust line in which the pressure is somewhat above atmospheric pressure.

Fluid will be introduced at a predetermined pressure into high pressure line 200, and through line 410 to a spring actuated relief valve 412, the fluid being discharged from the valve through lines 414 and 416, wherein line 416 is in open communication with exhaust line 406, and wherein line 414 is in communication with intake 418 of a double-acting, two-way valve 420 which is normally maintained in the position illustrated in the drawing by means of spring 422 whereby fluid entering port 418 will be discharged via line 424 into exhaust line 416. In this manner the net pressure of fluid in line 200 will be considerably reduced, thereby lessening the energy required to operate pump 400 and precluding undue heating of the pressure media.

A double-acting, four-way reversing valve 426 is normally conditioned by means of spring 428 to connect line 430 in open communication with line 432 to end 434 of the cylinder 166 which, through piston rod 164, actuates feed arm 142 about shaft 148 for normally disposing the said feed arm in a fully elevated position.

A solenoid indicated generally by the numeral 436 is adapted to reverse valve 426 whereby fluid under pressure from line 430 will be introduced into line 438 which is in open communication with end 440 of cylinder 166. 5 Line 442 is in open communication with line 438 for transmitting the pressure within line 438 and end 440 of cylinder 166 to a pressure switch 444.

Exhaust line 406 is connected to the discharge port 446 of valve 426 via line 448. Drain line 404 is suitably connected through line 450 to that side of valve 426 with which spring 428 is associated for returning any leakage which might occur in the valve back to sump or container 402.

End 452 of cylinder 250 is normally connected in open communication with pressure line 200 through line 454 to intake 456 of a double acting valve 458, line 460, rate valve 462, check valve 464 and lines 466 and 468. A second rate valve 470 is connected between lines 460 and 468 by lines 472 and 474, it being noted that a double 20 acting valve 476 controls the flow of fluid through rate valve 470. A spring 478 normally maintains valve 476 in closed condition, said valve being opened incident to energization of solenoid 480 for establishing a flow of fluid through the last mentioned rate valve.

Spring 459 normally maintains valve 458 whereby line 460 is in open communication with line 454. A solenoid 461 is provided for actuating this valve for selectively connecting line 482 in open communication with line 454.

15 The spring loaded ends or other portions of the housing of each of valves 458 and 476 are connected to drain line 404 by lines 484 and 486, respectively. Each of the rate valves 462 and 470 are likewise connected via lines 488 and 490 to the drain line 404.

20 From the foregoing it will be noted that end 452 of cylinder 250 will be normally subjected to fluid pressure for disposing feed wedge 220 in a fully advanced position for elevating post 210.

Fluid from line 200 is likewise supplied to double-40 acting valve 120 via line 492 for distribution through lines 494 and 496 to one or the other of cylinders 94 and 96, the pistons 90 and 92 of which, note Fig. 18, engage opposite ends of power rack 58.

The intake 498 of pilot valve 116 is connected by line 495 45 500 to pressure line 200, and when this valve is in the position illustrated in Fig. 22, the fluid of line 500 will be introduced into cylinder 502 through line 503 for shifting valve 120 for introducing fluid into cylinder 96, it being understood that the pilot valve is actuated by dogs 108 and 110 contacting levers 112 and 114, see Fig. 18. When lever 114 has been shifted to the left, fluid from line 500 will be introduced through line 504 to cylinder 506 for introducing fluid from line 492 into cylinder 94 via line 494.

50 Line 507 connects outlet port 508 of valve 120 in open communication with double-acting valve 510 which is normally closed by spring 512 for thereby precluding a flow of fluid through line 492 whereby pistons 90 and 92 will remain stationary. A solenoid 514 is provided for actuating valve 510 to an open position connecting line 507 with line 516, through an adjustable rate valve 518 to exhaust line 406 via line 520. The rate valve is connected to drain line 404 by line 522.

55 A solenoid 524 is provided to actuate valve 420 for blocking the flow of fluid therethrough to line 416, thereby increasing the pressure of fluid in line 200. A suitable filter 530 is provided in exhaust line 406 and a safety valve 532 is placed in parallelism with the filter for precluding damage thereto incident to clogging thereof.

60 65 70 After the pump 400 has been operated for providing fluid under pressure in line 200, and after an article has been mounted on the upper cradle, the operator may then initiate a cycle by which a flow of coolant is established, motor 146 started for driving belt 130 and sole-

noids 436, 480 and 524 energized. Energization of solenoid 436 will actuate valve 426 for applying fluid under high pressure to end 440 of cylinder 166 for rapidly lowering feed arm 142 until button 212 engages the free upper end of post 210.

Energization of solenoid 480 will place rate valve 470 in open communication between lines 472 and 468.

Energization of solenoid 524 actuates valve 420 to block the flow of fluid therethrough for placing line 200 under high pressure.

A pressure build up will occur in end 440 of cylinder 166 after the initial rapid lowering motion of feed arm 142 has been checked by post 210. This build up in pressure actuates the pressure switch 444 for closing an electrical circuit to solenoids 461 and 514 for actuating valves 458 and 510, respectively, to introduce fluid from line 454 to line 482 and connect line 460 with exhaust 406 via line 411, for retracting the feed wedge 220, thereby lowering post 210; and for simultaneously placing exhaust line 507 in open communication with line 516 for permitting fluid to flow from one or the other of cylinders 94 and 96 for reciprocating the power rack 58.

When limit switch 260, see Fig. 15, has been actuated, solenoid 480 is de-energized for actuating valve 476 to interrupt a flow of fluid, through 472 so that the exhaust of fluid from end 452 of cylinder 250 is restricted to line 466, thereby providing a slow feed of the feed wedge 220 and a very slow lowering of post 210.

As best illustrated in Fig. 15, a limit switch 351 is mounted whereby it will be actuated by the free outer end 258 of rod 254 as feed wedge 220 reaches the end of its stroke. Switch 351 opens an electric circuit to a so-called tarry timer, not illustrated, which initiates a short dwell after the post 210 has been fully lowered for thereby permitting the grinding operation to continue for a moment or two with the conjugate form, endless belt and article being ground in fixed relationship for thereby enabling so-called "spark-out" to occur, and to allow any deflections induced incident to the grinding operation to be relieved.

Upon termination of the cycle of the tarry timer, the electrical circuit to solenoid 436 is interrupted and spring 428 will actuate valve 426 whereby fluid will be applied to end 434 of cylinder 166 for thereby shifting arm 142 to its fully elevated position in the case of the convex machine illustrated in Fig. 11.

At the same time switch 363 is energized so that actuation of overriding lever 1363 by dog 361 secured to and carried by control rack 106 will result in de-energization of each of solenoids 461, 514 and 524, it being noted that the cradle will thus be stopped in the same relative position at the termination of each grinding cycle.

The grinding belt and flow of coolant are likewise stopped concurrently with the de-energization of solenoids 461, 514 and 524.

Suitable means are preferably provided for enabling the cradle and its associated driving rack to be actuated by hand during those periods of time when the device is being manipulated incident to set-up. Such means may comprise a needle valve 550 disposed between lines 494 and 496, thereby permitting the fluid in each of cylinders 94 and 96 to freely pass from one cylinder to another incident to axial movement of the rack.

Concave grinding

In those instances wherein it is desirable to grind the concave surface of an article, we prefer to utilize the device illustrated in Figs. 1 through 10. At the outset it may be noted that the primary distinction between convex grinding and concave grinding, by our method, amounts to a mere reversal of parts, in the sense that in convex grinding we propose to mount the conjugate form in a stationary position and of then moving the article to be ground about the fixedly mounted form in such a manner that the surface of the form will be disposed in

conjugate coincidence with the surface of the article being moved thereabout. When grinding concave surfaces we fixedly mount the article to be ground relative to the conjugate form which is moved relative to the fixedly mounted article for disposing the surface of the form in conjugate coincidence with the surface of the article incident to movement of the form relative thereto. In both grinding operations an endless belt is caused to pass over and is guided by the conjugate form, the grinding operation being accomplished by reason of effecting contacting relationship of the article with the abrasive surface of the belt as guided by the conjugate form.

With particular reference now to Fig. 1, the numeral 166 denotes a cylinder one end of which is pivotally secured as at 168 to a bracket 169 secured to and projecting downwardly from the housing 31. Piston rod 164 is pivotally secured as at 161 to the lower end of lever 159 the upper end of which lever is keyed to shaft 149 for rotation therewith. One end of the feed arm 143 is provided with a clamp 141 which is securely though releasably anchored to shaft 149 by means of bolts, or the like, 145. A bearing bracket 151 is suitably secured to a side wall of the housing as by a weld, said bracket rotatably receiving the outer end of shaft 149, note Fig. 2. The numeral 123 denotes a pad to which an article to be ground is securely though releasably attached.

The introduction of fluid under pressure into the left end of the cylinder 166 will shift the piston rod 164 to the right for thereby elevating feed arm 143 upwardly about shaft 149.

With particular reference now to Figs. 2 and 8, it will be noted that free, unrestrained upward movement of feed arm 143 will be resisted by the upper end of abutment 213 with the free lower end of pin 215.

The numeral 211 denotes a post which is identical with and a substantial duplicate of post 210 as more fully detailed in Fig. 13, it being further understood that axial movement of post 211 is accomplished by the same or a similar mechanism illustrated in Fig. 13 for controlling the axial movement of post 210.

Upward axial movement of pin 215 is translated to a parallel, downward axial movement of rack or counter shaft 217 the lower end of which may terminate in a rod-like portion 229 the free end of which may abuttingly engage the free upper end of post 211.

As clearly illustrated in Fig. 8, pin 215 is integral with a rack 221, the teeth of which engage the teeth of a pinion gear 223 rotatably mounted for movement about shaft 225 the opposite ends of which shaft are supported by and spannably engage a pair of duplicate side plates 227 of housing 233. The teeth of gear 223 are likewise in engagement with the teeth of rack 217 wherein the axis of racks 221 and 217 are in spaced parallelism whereby movement of one rack in one direction will produce an equal and opposite movement of the other rack.

With reference now to Fig. 9, it will be noted that the free lower end of rod 229 is adapted to abuttingly engage the upper surface of an offset plate 231 secured to and carried by the free upper end of post 211. It should, of course, be understood that the free lower end of pin 229 could be in axial alignment with post 211, however we have ascertained that by using offset plate 231, as illustrated, an alignment problem is effectively solved without in any way impairing the efficiency of the device.

Referring again to Fig. 8, it will be noted that the racks 221, 217, gear 223 and shaft 225 may be secured to and housed within a bracket 233 secured by means of bolts 235 to wall 237 of the frame.

It will be understood that upward movement of feed arm 143 will thus be resisted by the counter-force of post 211 by means of actuation of wedge 220 of Fig. 13.

As earlier indicated in concave grinding we propose to move the conjugate form along a predetermined path during the grinding operation. The particular means utilized to accomplish the desired motion of the conjugate

form is best illustrated in Fig. 3. The numeral 900 denotes a spindle rotatably journaled in bearings 902 and 904 within housing 906. A gear sleeve 908 is keyed to spindle 900, said sleeve having two sets of teeth 910 and 912 therearound, teeth 910 engaging the teeth of power rack 914. Gear 912 engages the teeth of control rack 916 to which dogs 918 and 920 are secured.

A cam shaft 922 is mounted interiorly of but offset from the axial center of spindle 900 in which it is rotatably mounted on bearings 924 and 926, whereby the axis of the cam shaft is disposed in spaced parallelism with the axis of spindle 900.

A housing 930 is secured to and in axial alignment with housing 906 by means of bolts 932, note Fig. 4, said housing containing a stationary internal gear 934 with which the teeth of a planet gear 936 mesh, said planet gear being keyed to cam shaft 922, whereby rotation of the planet gear 936 will result in rotation of the cam shaft.

The numeral 950 denotes generally a conjugate form, or cam, the outer surface of which has been accurately formed in such a manner that the resultant motion imparted to cam shaft 922 incident to reciprocation of power rack 914 will result in the sequential presentation of portions of the surface of same cam in conjugate coincidence with the concave surface of an article secured to and carried on pad 123 of feed arm 143. The conjugate form 950 may be secured to and in axial alignment with cam shaft 922 by means of mounting bolts 952.

With reference now to Fig. 1, the numeral 960 denotes a shoe which engages the endless abrasive belt 130 as it approaches the conjugate form 950, whereas the numeral 962 denotes a belt tracking shoe which engages the belt after leaving the conjugate form.

In the preferred embodiment of the invention shoe 960 is in timed or driven relationship with conjugate form 950, whereas shoe 962 is merely a self-equalizing shoe which equalizes the tension throughout the width dimension of the belt leaving the conjugate form.

With particular reference now to Figs. 5 and 10, the numeral 964 denotes an axially shiftable follower roller 966 adapted to engage edge 968 of a cam plate 970 secured by means of bolts 972 to the control rack 916. Rod 964 is normally and yieldably urged toward cam plate 970 by means of rod 965 mounted within housing 967 secured by means of bolts 969 to housing 906. Rod 965 includes a free outer end 971 which is adapted to abuttingly engage the free outer end of cam rod 964, rod 965 being normally and yieldably urged into contacting relationship with rod 964 by means of a spring 974 interposed between a rack 978 and the end of a counter bore in end cap 976. Rod 965 is externally threaded whereby to engage the internally threaded portion of the rack. The free outer end of rod 965 may be slotted as at 980 for accommodating the blade of a screw driver thereby enabling an operator to turn the rod relative to the rack. A lock nut 982 engages the free outer threaded end of the rack.

A gear segment 984 secured to and carried by shaft 986 engages teeth of rack 978 for imparting rotary motion thereto and to shoe 960 secured to and carried by shaft 986.

From the foregoing it will be noted that axial movement of rod 965 will effect tilting or turning of shoe 960 about shaft 986 for thereby presenting the belt to the conjugate form 950 in phase with that particular surface of the conjugate form over which the belt passes incident to its grinding operation, the particular degree of tilt being determined by the characteristics of cam plate 970.

With reference now to Figs. 1 and 11, it will be noted that shoe 962 is substantially U-shaped in cross section comprising a pair of laterally spaced, substantially parallel front and rear walls interconnected by a bottom wall. The lateral spacing of the front and rear walls is equal to the width of belt 130 plus a clearance sufficient to enable the belt to pass freely between the said side walls.

A presser plate 1000 is mounted between the front and rear walls of shoe 962 said plate having a rear surface disposed in spaced parallelism with the bottom wall of the shoe for thereby defining a passageway through which the belt passes. Shoe 962 is pivotally mounted relative to extension 1002 of a clamp element 1004 secured to and carried by shaft 1006 which is secured to and projects from the feed arm 142 in the case of the convex machine of Fig. 11, and from wall 237 of housing 31 in the case of the concave machine of Fig. 1.

The operating characteristics of shoe 962 are as follows: If the tension throughout the width of the belt should become unequal whereby one edge of the belt would tend to become longer than the opposite edge, the shorter side will bear against the shoe which will be moved about its pivotal connection with extension 1002 thereby equalizing the tension across the belt.

It will likewise be noted that shoe 962 provides simple yet effective means for precluding accidental or unintentional disengagement of the belt from the conjugate form over which it passes, particularly when the belt is started up from a condition of rest. In this manner we have provided highly effective means for automatically compensating for unequal tension across the width of belt 130 incident to its passage over and upon leaving the conjugate form.

With reference now to Figs. 1, 5, 6 and 7 the numerals 700 denote coolant nozzles which project from the forward face of housing 906, each of said nozzles, note Fig. 30 7, being provided with a plurality of apertures 702 through which a suitable coolant may be discharged onto the article being ground and onto both sides of the abrasive belt. Coolant under pressure is supplied to nozzles 700 by means of flexible conduits 704.

With reference now to Figs. 4 and 5, it will be noted that dogs 918 and 920 are adapted to engage levers 112 and 114, respectively, of a pilot valve 116, it being understood that the action of this pilot valve in the case of the concave machine of Figs. 1 through 10 is identical with 40 the action of corresponding pilot valve 116 best illustrated in Fig. 18 of the convex machine.

It will be understood that in the case of both the concave and convex machines the coolant is collected, returned to a sump and re-circulated in a manner well known 45 to the art.

The terms mounting means and/or mounting members have been used in the claims as indicating those means and/or members to which the article to be ground, and to which the conjugate belt shaping form is mounted. By 50 way of example, shaft 922 of Fig. 3, to which the conjugate 950 is mounted by means of bolts 952 is the mounting means for said form; and feed arm 143 comprises the mounting means for the article to be ground.

In the case of the convex machine, the article mounting 55 means comprises the inner cradle 34, and the associated mechanism for driving it, whereas the mounting means for the conjugate form comprises feed arm 142.

By way of summary, it will be noted that in those instances wherein a concave surface is being ground, such 60 as, by way of example, when utilizing the mechanism illustrated in Figs. 1-11, a true rolling contact is obtained between or relative to the outer surface of the conjugate form 950, and corresponding portions of the article to be ground. In other words, a different portion of the cam 65 surface will be disposed relative to each different section of the surface of the article incident to the periodically reversed cyclic motion of the form over which the endless abrasive belt passes.

In the case of convex grinding, the resultant motion 70 between the conjugate form and the surface of the article being ground is substantially a rolling contact, there being some slippage between the form and the article, as is apparent from an inspection of Figs. 20 and 21, wherein it will be noted that the linear distance along the 75 outer surface 140 of the conjugate form 141 between the

adjacent points of contact of the article in the various positions denoted by the letters C1, C2, C3 and C4 is greater than the linear distance along the convex surface of the article itself between the same adjacent points. That is, one point on the surface of the conjugate form will touch or be disposed relative to but one point on the surface of the article C, however each point on the surface of the article may be common to several points on the surface of the form, especially near the trailing edge of the article.

The present invention is neither directed to nor concerned with the particular fastening means by which an article to be ground is mounted, however the manner in which the article is aligned with reference to the form is of prime importance, particularly in those instances when the surface to be ground is an airfoil section as illustrated in Figs. 20 and 21.

The root end of the blades or buckets of a turbine type engine are provided with and terminate in a mounting member which in most instances is an integral part of the blade or bucket. These mounting members are adapted to support the blades or buckets in predetermined relationship with other portions of the engine of which they form a part.

The root of each blade has or bears a certain fixed relation in space with respect to the airfoil sections of the blade, and in most blades the airfoil sections are laid out according to a system of x, y and z coordinates, wherein the x and y coordinates are in a common plane and the z coordinate in another plane. When using such a system the z coordinate can be considered to be the axis of the blade and the airfoil sections laid out on the x and y coordinates.

In practicing our method of grinding, the fastening means are so disposed that the airfoil surface of the blade is presented to the conjugate surface of the shaping form so that the shape generated will bear the proper relation to the root of the finished blade.

Quite obviously the outer surface of the shaping form over which the endless abrasive belt passes is so formed that as the desired relative motions, hereinbefore described, occur the desired airfoil contour will be ground into the blade.

Referring now to Figs. 20 and 21, it will be noted that the thinner end of the blade sections illustrated is the trailing edge and that the thicker end is the leading edge. The relationship between the form and article being ground is such that the blade is out of contact with the abrasive belt passing over the form at each or opposite ends of each of the periodically reversed grinding cycles, note articles C and C5 in Figs. 20 and 21.

In the preferred embodiment of the invention the effective length of form 141 and 950 is approximately equal to the length of a blade to be ground between its root and tip, and the width of the endless abrasive belts 130 are at least equal to the length of the forms, so that approximately the entire airfoil surface on one side of the blade will be developed during a grinding operation.

From the foregoing it will be noted that we have provided a simple yet highly effective method and means for rough and/or finish grinding to exact standards the airfoil surfaces of the buckets and blades of turbine type engines whereby air foil surfaces may actually be generated and then finished all by a grinding operation, the resultant product being entirely free of so-called "feed lines" inherent in blades formed by contour machining methods.

By means of our method and apparatus it is feasible and commercially practical to remove up to .300 inch of stock from each side of blades fabricated from the new alloys which are characterized by their extreme toughness, whereby each blade so produced will be interchangeable with all similar blades, our method of airfoil generation insuring exact weight and shape characteristics of each blade.

It should be understood that our method may be prac-

ticed by hand or by suitable mechanical means and that the devices illustrated are exemplary rather than restrictive of mechanical means useful in practicing the subject method of grinding.

5 Various changes in the structural details of the devices may be made, within the scope of the appended claims, without departing from the spirit of the invention.

What is claimed is:

1. The method of grinding convex or concave surfaces on irregularly shaped articles by means of an abrasive belt passing between a conjugate form as one member and the surface of the article as another member, which method comprises the steps of mounting one of said members, for planetary movement relative to the other member, of imparting oscillating planetary motion to the movably mounted member for sequentially disposing portions of the surface of the form in conjugate coincidence with portions of the surface of the article for and throughout at least a major portion of said planetary movement, of passing an endless abrasive belt over the form and of then effecting contact of the article with the abrasive side of the belt.

2. The method of grinding concave surfaces on articles by means of an abrasive belt passing between a conjugate form and the surface of the article, which method comprises the steps of providing the outer surface of the form with a surface contour which when rotated will make rolling contact with the concave surface to be ground in the article, of imparting a periodically reversed planetary motion to the form, of passing an endless abrasive belt over the moving form, and of then moving the article into contacting relationship with the abrasive side of the belt while maintaining the article in a fixed plane throughout the entire grinding operation.

3. The method of grinding convex surfaces on articles by means of an abrasive belt passing between a conjugate form and the surface of the article, which method comprises the steps of providing the form with a conjugate surface contour of the convex surface to be ground in the article, of mounting the form in a fixed plane, of imparting a periodically reversed planetary motion to the article, of passing an endless abrasive belt over the stationary form, and of then moving the form for disposing the abrasive side of the belt into contacting relationship with the article while maintaining the form in a fixed plane throughout the entire grinding operation.

4. In a grinder of the endless abrasive belt type, mounting means for a shaping form over which the belt passes, a conjugate shaping form secured to and carried by said means, mounting means for an article to be ground, means for imparting a periodically reversed planetary motion to one of said mounting means for sequentially disposing the adjacent portions of the surface of the form in relative conjugate coincidence with the surface of the article, means for imparting substantially straight line movement of the other mounting means relative to the said first mentioned mounting means for effecting contact of the article with the abrasive face of the belt passing over said form.

5. In a grinder of the endless abrasive belt type, a first mounting means for a shaping form over which the belt passes, a conjugate shaping form secured to and carried by said means, a second mounting means for an article to be ground, means for imparting periodically reversed planetary motion to the second mounting means for sequentially presenting portions of the surface of the article carried thereby in relative conjugate coincidence with the surface of the form, means for imparting substantially straight line movement of the first mounting means relative to the second mounting means for effecting contact of the article with the abrasive face of the belt passing over said form.

6. In a grinder of the endless abrasive belt type, a first mounting means for a stationary shaping form over which the belt passes, a conjugate shaping form secured

75

to and carried by said means, a second mounting means for an article to be ground, said last mentioned means including an inner cradle and an outer cradle, means for clamping an article to the inner cradle, means for oscillating the outer cradle about a fixed axis, a sun gear fixed relative to the outer cradle, means pivotally suspending the inner cradle from the outer cradle, a planet gear fixed relative to the inner cradle and in driven relationship with the said sun gear, whereby oscillatory movement of the outer cradle will sequentially present portions of the surface of the article carried by the inner cradle in substantial rolling contact with portions of the form, means mounting the first mounting means for substantial straight line motion radial to the fixed axis about which the outer cradle is moved for effecting contact of the article to be ground with the abrasive face of the belt passing over the said conjugate form, and means for imparting movement to said first mounting means.

7. A grinder as set forth in claim 6, in which the means for imparting movement to the first mounting means is continuously operable during the entire grinding cycle, and wherein free movement of the said mounting means is resisted and controlled by a movable feed control member, and means operable for sequentially actuating said control member at different feed rates.

8. A grinder as set forth in claim 6, in which the means for imparting feeding movement of the first mounting means is continuously operable during the entire grinding cycle, and wherein initial free feeding movement of the said means is resisted and controlled by a movable member, means operable for initially actuating said member at one rate of feed and then at a slower rate of feed for the duration of the grinding cycle, and means operable upon termination of the grinding cycle for reversing the feeding movement of the means for imparting feeding movement to the first mounting means for retracting the form relative to the said fixed axis.

9. A grinder as set forth in claim 6, which includes a belt tracking shoe over which the belt passes after leaving the form, and means pivotally mounting the shoe relative to the first mounting member and for free movement relative to and transversely of the belt in response to variations in tension across the width of the belt for equalizing the tension across the width of the belt as it passes over said shoe.

10. In a grinder of the endless abrasive belt type, a first mounting means for a shaping form over which the belt passes, a conjugate shaping form secured to and carried by said means, a second mounting means for supporting in a fixed plane an article to be ground, means for imparting a periodically reversed planetary motion to said first mounting means for sequentially presenting portions of the surface of the form in rolling contact relative to the surface of the article, means for imparting substantially straight line movement to the second mounting means relative to the said first mounting means for effecting contact of the article with the abrasive face of the belt passing over said form while maintaining the article in said fixed plane.

11. In a grinder of the endless abrasive belt type, a first mounting member for an article to be ground, means for securely though releasably clamping an article thereto, a second mounting member for a shaping form over which the belt passes, said last mentioned means including a spindle, means for alternately rotating the spindle in opposite directions about a fixed axis, an internal sun gear fixed relative to said spindle, a shaft journaled within and rotatable about an axis in spaced parallelism with the axis of the spindle, means for attaching a shaping form to and projecting forwardly of said spindle, a planet gear fixed relative to the shaft and in driven relationship with the internal sun gear, whereby alternate rotary motion of the spindle will sequentially present portions of the surface of the form carried by the shaft in rolling contact with portions of

the article carried by the first mounting member, means mounting the first mounting member for substantial straight line motion radial to the fixed axis about which the said spindle rotates for effecting contact of the article to be ground with the abrasive surface of the belt passing over the said form, and means for imparting feeding and retracting movement to said first mounting member.

12. A grinder as set forth in claim 11, which includes 10 a belt guiding and tracking shoe over which the belt passes just prior to passing over the shaping form, means pivotally mounting the shoe for controlled movement relative to and transversely of the belt, means in synchronization with the means for rotating the said spindle and in driving relationship with said shoe to move the shoe in timed relationship with the movement of the form for presenting the belt flatwise onto the form for all positions of the form throughout its planetary cycle.

13. A grinder as set forth in claim 11, which includes 20 a belt guiding and tracking shoe over which the belt passes prior to passing over the shaping form, means in timed relationship with the form for actuating said shoe for presenting the belt flatwise onto the form, and a belt tracking shoe over which the belt passes after leaving the form, means pivotally mounting the second shoe for free movement relative to and transversely of the belt in response to variations in tension across the width of the belt for equalizing the tension across the width of the belt as it passes over said shoe.

14. In a grinder of the endless abrasive belt type, 30 mounting means for a shaping form over which the belt passes, mounting means for an article to be ground, means for imparting a periodically reversed, cyclic motion to one of said mounting means relative to a fixed, stationary axis for sequentially disposing successive portions on the surface of a form secured to and carried by one of the mounting means in relative conjugate coincidence with successive portions on the surface of an article secured to and carried by the other mounting means, means for initiating said cyclic motion to said one mounting means and for simultaneously initiating a feeding cycle of the other mounting means for advancing it in substantially straight line movement radially of the stationary axis about which the first mentioned 40 mounting means is moved for effecting contact of an article carried by one of said mounting means with the abrasive face of an endless belt passing over a form carried by the other of said mounting means, means for providing a three speed feeding cycle comprising a first or rapid feed for effecting initial contact of the article with the abrasive belt, a second, slower feed rate during the initial grinding operation, and a third or slow feed rate during the finish grinding operation, means operable at the end of the termination of the third feed 45 rate for retracting the said mounting means and for then terminating the cyclic motion of the other mounting means.

15. In a grinder as set forth in claim 14, which includes means for initiating a short dwell period at the 50 termination of the feeding cycle and before initiation of the retraction cycle, and means for terminating the cyclic motion of the other mounting means at a definite and predetermined phase of its cycle.

16. The method of grinding convex and concave airfoil surfaces on blades for a turbine type of engine by 55 means of an abrasive belt passing between a form as one member and a surface of the blade as another member, which method comprises the steps of providing the form with a developed surface the conjugate of and equal to the length of the airfoil surface to be developed 60 in the blade, of mounting one member, for oscillatory movement relative to the other member, of imparting oscillating motion to the movably mounted member for sequentially disposing portions of the form in conjugate coincidence with portions of the airfoil surface of

the blade, of passing an endless abrasive belt having a width at least equal to the length of the developed surface of the form over said form, and of then effecting contact of the airfoil surface of the blade with the abrasive side of the belt.
